Application November 14, 1947, Serial No. 142,518

Term of patent 14 years

(Cl. D44—26)

To all whom it may concern:

Be it known that we, Edwin G. Polan and Harry H. Metcalf, citizens of the United States, residing at Huntington, in the county of Cabell and State of West Virginia, have invented a new, original, and ornamental Design for a Filter Rod for a Coffee Maker, of which the following is a specification, reference being had to the accompanying drawing, forming a part thereof.

In the drawings:

Figure 1 is a perspective view of a filter rod for a coffee maker showing our new design;

Fig. 2 is an elevational view; and

Fig. 3 is an end view thereof.

We claim:

The ornamental design for a filter rod for a coffee maker, substantially as shown.

EDWIN G. POLAN.
HARRY H. METCALF.
